UNITED STATES PATENT OFFICE.

HORATIO C. RANDALL, DECEASED, LATE OF SAN FRANCISCO, CALIFORNIA, BY ANNA L. RANDALL, EXECUTRIX, OF SAN FRANCISCO, CALIFORNIA.

HYDRAULIC-ELEVATOR-CONTROL SYSTEM.

1,372,191.

Specification of Letters Patent. Patented Mar. 22, 1921.

Application filed October 13, 1919. Serial No. 330,455.

To all whom it may concern:

Be it known that HORATIO C. RANDALL, deceased, in his time a citizen of the United States, and a resident of the city and county of San Francisco, State of California, did in his lifetime invent a certain new and useful Hydraulic-Elevator-Control System, of which the following is a specification.

The invention relates to elevator control systems and particularly to control systems for hydraulic elevators.

An object of the invention is to provide means for preventing creeping of the elevator car, due to leaky valves or other causes, when an elevator shaft door is unlocked.

Another object of the invention is to provide means operative by the unlocking of a shaft door for throwing the control mechanism into operation.

The invention possesses other advantageous features, some of which, with the foregoing, will be set forth at length in the following description, where that form of the invention which has been selected for illustration in the accompanying drawings, will be outlined in full. In said drawings is shown one embodiment of the invention, but it is to be understood that the invention is not limited to such form, since the invention, as expressed in the claims, may be embodied in a plurality of forms.

Referring to said drawings:

Figure 1 is an elevation of an elevator shaft and an elevator car therein equipped with the apparatus of this invention.

Fig. 2 is a front elevation of the elevator control lever actuating means carried by the car.

Fig. 3 is a vertical transverse section of the mechanism shown in Fig. 2.

Difficulty is experienced in the operation of hydraulic elevators, due to the creeping of the elevator car when the control lever is in neutral position. This difficulty is particularly noticeable when the car is brought to a stop at a floor. The present invention contemplates the provision of means for moving the control lever from neutral position in a direction to counteract the creeping of the car, and thereby hold the car stationary, and this means is thrown into operation by the unlocking of an elevator shaft door.

The elevator shaft is provided at each floor with a lock 2 which is engaged by a bolt 3 carried by the shaft door 4, for hold-

ing the door locked in the closed position. This lock is preferably constructed as shown in the copending application of H. C. Randall, Serial No. 283,852, filed in the Patent Office on March 20, 1919. Each lock is 60 provided with an actuating lever 5 projecting from the lock casing and adapted to be rocked to release the bolt 3, by the shoe 6, carried by the elevator car and movable into position to actuate the lever 5 by the pedal 65 7. Depression of the pedal moves the shoe into position to actuate the lever 5, and the pedal is usually depressed as the elevator approaches a floor at which passengers are to be taken on or discharged, so that the 70 door is unlocked as the elevator car moves into position. The pedal, however, may be operated to unlock the door after the car has been brought to rest at a floor.

Disposed in the elevator shaft is a vertically movable, vertically disposed wire 8 weighted at its lower end and supported at its upper end by a spring 9, so that it is vertically movable. The wire is provided at points adjacent the locks 2 with fixed enlargements or abutments 12 and each lock is provided with a lever 13, connected to the actuating lever 5, and slidably engaging the wire immediately below the adjacent abutment 12. Consequently, when the lever 5 is 80 moved to unlock the door, the lever 13 is 85 raised, raising the wire 8. When the lever 5 is released, the wire moves downward to its normal position.

Carried by the wire adjacent its upper 90 end is a slide comprising a conducting portion 14 and two insulating portions 15, on either side of the conducting portion. Arranged on opposite sides of the slide and contacting therewith are two fixed contacts 95 16-17 of the electric circuit 18. When the wire is in the normal position, the contacts 16-17 engage an insulating portion 15, maintaining the electric circuit 18 open, but when the wire is raised, the conducting portion 14 is moved into engagement with the contacts 16-17, closing the circuit. Arranged in the circuit is a source of current, such as the battery 19 and a solenoid 21, carried by the elevator car.

The movement of the car is controlled by the lever 22, secured to the shaft 23, which is suitably connected to the valves of the hydraulic motor. Movement of the control lever in one direction from its neutral posi-

105

110

tion causes the hydraulic motor to operate to raise the car and movement of the lever in the opposite direction causes the hydraulic motor to operate to lower the car. Means are provided for causing a creeping movement of the car to move the control lever 22 in a direction to counteract the creeping movement.

Depending from the car are a pair of vertical guides 24, upon which is disposed a vertically movable carriage 25, the carriage being provided with rollers 26 engaging the guides and being provided with a counter-weight 27. Disposed in the elevator shaft 10 is a fixed vertical member or cable 28 which is also engaged by rollers 29, journaled on the carriage. Means are provided for clamping the carriage to the fixed vertical member 28, so that the carriage is held stationary in the shaft and this means is operated by the unlocking of a shaft door. Arranged in the carriage is a cylinder 31, having a spring-pressed piston 32 therein, to which is secured the piston rod 33. Secured to the outer end of the piston rod, is a shoe 34, which is adapted to be moved by the piston, to clamp the cable 28 to the carriage. The piston is operated by fluid under pressure, preferably air, which is conveyed to the car through the flexible conduit 35. Disposed in the flexible conduit and mounted on the car is a three-way valve 36, the operating lever 37 of which is connected to the core 38 of the solenoid 21. When the solenoid circuit is closed, the valve 36 is operated to admit fluid under pressure into the cylinder and clamp the carriage to the fixed cable 28. When the circuit is opened, the core 38 moves the valve into position to permit the air in the cylinder to exhaust into the atmosphere and the spring 39 then moves the piston to release the carriage from the fixed cable. It is apparent, therefore, that when the solenoid circuit is closed, that the carriage is held against vertical movement, so that a movement of the car causes a relative movement of the car with respect to the carriage. This movement is employed to move the control lever 22 in a direction to counteract the movement of the car. Secured to the shaft 23 is a lever 41 having a forked end 42 engaging the piston rod 33, so that as the carriage moves relatively to the car, the shaft 23 is moved to actuate the valves in the hydraulic motor 43 in such manner as to stop the movement of the car.

What is claimed is:

1. The combination with an elevator shaft 60 provided with doors, of an elevator car in said shaft, a hydraulic motor for moving said car, a lever for controlling the operation of said motor, locks for holding said doors closed, means operative by a movement of the car for moving said lever, and

means operative by the unlocking of a door for throwing said last-named means into operation.

2. The combination with an elevator shaft 70 provided with doors, locks for holding said doors closed, an elevator car in said shaft, a hydraulic motor for moving said car, means carried by the car for controlling said motor, and means thrown into operation by the unlocking of a door for causing 75 a movement of the car to actuate said controlling means.

3. The combination with an elevator shaft 80 provided with doors, of locks for holding the doors closed, an elevator car in said shaft, a hydraulic motor for moving said car, a motor controlling device, a vertically movable carriage on the car connected to said device, a fixed vertically disposed member in said shaft normally slidably engaged 85 by said carriage, and means operative by the unlocking of a door for clamping said carriage to said fixed vertical member.

4. The combination with an elevator shaft 90 provided with doors, of locks for holding the doors closed, an elevator car in said shaft, a hydraulic motor for moving the car, a motor controlling device on said car, a movable carriage on said car connected to said controlling device, and means operative 95 by the unlocking of a shaft door for clamping said carriage against movement, whereby a movement of the car produces a relative movement of the car with respect to the carriage.

5. The combination with an elevator shaft 100 provided with doors, of locks for holding the doors in closed position, an elevator car in said shaft, a hydraulic motor for moving said car, a motor control device, a fixed vertically disposed member in said shaft, a vertically movable carriage on said car connected to said control device and normally out of tight engagement with said vertically disposed member, means on the carriage adapted to clamp said member, and means operative by the unlocking of a door for moving said clamping means to engage said member.

6. The combination with an elevator shaft 115 provided with doors, of locks for holding said doors in the closed position, an elevator car in said shaft, a hydraulic motor for moving said car, a motor control device carried by the car, a vertically movable carriage arranged on said car and connected to said control device, a fixed vertical element in said shaft associated with said carriage, means for clamping said carriage to said element, electromagnetic means controlling the actuation of the clamping means, and means operative by the unlocking of a door for actuating said electromagnetic means.

7. The combination with an elevator shaft 130

provided with doors, of locks for holding said doors in the closed position, an elevator car in said shaft, a hydraulic motor for moving said car, a control device for said motor, a vertically movable carriage on the car connected to said control device, a vertically disposed fixed cable in said shaft with which said carriage normally makes free sliding contact, a cylinder on said carriage, a piston in said cylinder, means con-

nected to the piston for clamping the carriage to the cable, a valve for controlling the flow of fluid under pressure to and from said cylinder, a solenoid for moving said valve, a circuit for said solenoid and means 15 operative by the unlocking of a door for closing the solenoid circuit.

ANNA L. RANDALL,
Executrix of the estate of Horatio C. Randall, deceased.
